UNITED STATES PATENT OFFICE.

DAVID WASSERMAN, OF JERSEY CITY, NEW JERSEY.

CORNER FASTENING FOR BEDSTEADS.

Application filed June 21, 1923. Serial No. 646,794.

To all whom it may concern:

Be it known that I, DAVID WASSERMAN, a citizen of the United States, and resident of Jersey City, in the county of Hudson and State of New Jersey, have invented certain new and useful Improvements in Corner Fastenings for Bedsteads, of which the following is a specification.

The present invention relates to improvements in corner-fastenings for bedsteads, and has for its main object to provide a simple, efficient and durable device of this type which is capable of being readily, economically and conveniently struck up from sheet metal.

Another object of the invention is to produce a corner-fastening of the type mentioned, which permits of a convenient assembling of the bed and of taking down of the same, if desired, without the employment of tools.

A further object of the invention is to so construct the corner-fastening that the bottom supporting member may be clamped thereto or released therefrom without the employment of any movable parts on either the base of the corner-fastening or on the bed bottom supporting member, whereby not only the manufacture of the device is greatly cheapened, but the possibility of anyone of the elements of getting out of order eliminated.

A still further object of the invention is to so construct the corner-fastening that the bed-bottom supporting angle bar may be reversibly secured thereto, so as to adapt it to ordinary spring mattresses and also to box springs.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claim, without departing from the spirit or sacrificing any of the advantages of the invention.

Two of the many possible embodiments of the invention are illustrated in the accompanying drawings, in which:—

Figure 1 is a side elevation of a corner-

fastening, constructed in accordance with the present invention, in position upon the corner-post of a bedstead, the bed-bottom supporting angle bar being shown positioned to receive an ordinary spring mattress; Fig. 2 is a section taken on line 2—2 of Fig. 1; Fig. 3 is a side elevation of the angle bar employed in the construction shown in Figs. 1 and 2 of the drawings; Fig. 4 is a top plan view of the said angle bar; Fig. 5 is an elevation similar to the one shown in Fig. 1 of the drawings, showing the bed-bottom supporting angle bar positioned to receive a box spring; Fig. 6 is an elevation, similar to the one shown in Fig. 1 of the drawings, of a modification of the invention; and Fig. 7 is a section taken on line 7—7 of Fig. 6.

Referring now first to Figs. 1 to 5, inclusive, of the drawings, the numeral 10 indicates a portion of a tubular corner-post of a bedstead, to which the corner-fastening is to be attached. The corner-fastening includes a bracket 11, made for instance by stamping operations, and comprising a curved portion 12, which abuts against the corner-post, and a vertically extending side-wardly projecting plate element 13, that is made integral with the said curved portion; the said plate element extending longitudinally of the bedstead. The bracket may be fastened to the corner-post in any suitable manner, for instance by screw-bolts 14.

To the plate element 13 of the bracket is fastened in any suitable manner a stud 15, provided with a head 16, the latter being spaced from the said plate. Below the said stud and, preferably, to the side of the same, there is provided upon the plate element 13 a lug 17, projecting in the same direction as the said stud. This stud and lug are brought into engagement, in a manner presently to be described, with the bed-bottom supporting side rail, in the form of an angle bar 18, which is provided in one of its flanges, denoted by the numeral 19, and adjacent each end thereof with a slot 20, the two slots extending in parallel relation at right angles to the longitudinal axis of the bar and being provided centrally with an enlargement 21 so as to permit the head 16 of the respective stud 15 to pass therethrough. The width of each slot is somewhat larger than the diameter of the shank of the stud. In the free edge 22 of that flange of the angle bar in which the slots 20 are provided, there

are formed two notches 23, one adjacent each slot, said notches serving to receive the lugs 17 on the plate members 13. In alignment with each notch 23 is formed in the angle 5 bar, and more particularly at the junction of the two flanges thereof, an aperture 24, which is also capable of receiving a lug 17.

The bottom supporting angle bar may be mounted upon the bracket with the horizontal flange uppermost, as shown in Figs. 1 10 and 2 of the drawings, or with the horizontal flange lowermost, as shown in Fig. 4 of the drawings. In either position, the head 16 of the stud is passed through the slot 20 15 at its enlargement 21, and then the angle bar forced downwards as far as the slot permits, that is to say until the upper edge of the slot rests against the shank of the stud. When the horizontal web is uppermost, the lug 17 20 becomes seated in the notch 23, and when the horizontal flange rests lowermost, the said lug is seated in the aperture 24.

It will be seen that regardless of which of the two positions the angle bar is caused to 25 occupy, it is effectively prevented from shifting both longitudinally and laterally on the bracket, and also that it is at all times supported on each bracket on two points.

30 The bracket is made, as above stated, by stamping operations. The stud 15 is, preferably, a separate piece, attached to the said bracket, while the lug 17 may be either made separately and secured to the bracket, or it 35 may be struck up from the same piece of sheet metal.

The modification illustrated in Figs. 6 and 7 of the drawings differs from the one above described in that the outwardly projecting lug 17 is provided with a sideward-

ly extending projection 25, that extends parallel to the plate element 13 of the bracket. Furthermore that element of the bracket which abuts against the corner-fastening, and denoted in Figs. 6 and 7 of the drawings by the numeral 26, is flat, so as to be capable for cooperation with a corner-post of quadrangular transverse cross-section. Otherwise the construction and operation of the elements are the same as of those 50 described in connection with Figs. 1 to 5, inclusive, of the drawings.

It is to be noted that in the construction shown in Figs. 1 and 2 of the drawings the portion 12 of the bracket may be flat for cooperation with a corner-post of quadrangular transverse cross-section.

What I claim is:

A corner-fastening for bedsteads comprising 60 a bracket for attachment to a corner-post, a headed stud on said bracket, a lug formed on said bracket below said stud and at the side of the latter, and a side rail, angular in cross-section, having a slot in one 65 of its flanges provided with an enlargement to permit the head of said stud to pass, said flange being furthermore provided in its free longitudinal edge with a notch in which said lug is adapted to be seated, said enlargement being centrally disposed in relation to 70 said slot and said rail having an aperture at the junction of its flanges in alignment with said notch, thereby permitting said rail to be mounted upon said bracket either 75 with its horizontal flange uppermost or lowermost.

Signed at New York, in the county of New York, and State of New York, this 19th day of June, A. D. 1923.

DAVID WASSERMAN.
